EDWARD HOERICH, OF BALTIMORE, MARYLAND.

FLUSHING APPARATUS FOR WATER-CLOSETS.

1,132,719.

Specification of Letters Patent. Patented Mar. 23, 1915.

Application filed May 6, 1914. Serial No. 836,731.

To all whom it may concern:

Be it known that I, EDWARD HOERICH, a citizen of the United States, residing at Baltimore, in the State of Maryland, have 5 invented new and useful Improvements in Flushing Apparatus for Water-Closets, of which the following is a specification.

This invention relates to improvements in flushing apparatus for water-closets, and 10 proposes a construction of the "frost-proof" type, the chief characteristics of which are that the flush tank and the water supply and discharge pipes are normally empty; the admission of water to said tank is controlled 15 by a normally closed main valve which is suitably located under ground below the frost line; and the said main valve is employed in combination with an auxiliary valve which is normally open but is automatically closed during the period in which 20 the main valve is open and is used to control the water flowing past the main valve, causing said water to pass into the flush tank so long as the main valve is open and 25 thereafter and when the main valve is closed permitting it to pass through the flush pipe.

The object of the invention is to provide a construction of the type described having an improvement in the organization of its 30 parts whereby all of the operating elements, including the main valve and its seat, are removable and replaceable as a unit with respect to the pipe in which they are arranged, by virtue of which characteristic the 35 parts are quickly and readily accessible for the purposes of renewal, substitution or repairs; having other improvements in the organization and construction of certain parts whereby the opening of the main valve will 40 invariably be accompanied by a short preliminary and substantially immediate flushing of the closet bowl, and whereby this short preliminary flush is automatically terminated for an indeterminate interval prior 45 to the main flush which takes place consequent to the opening of the auxiliary valve above referred to; having other features connected with the construction of the operating means whereby the valves are positively 50 operated in either direction of movement and the auxiliary valve is positively held in closed relation; having certain further features of organization which provide for simplicity of mechanical structure and reliability and facility of operation; and 55 having a further improvement in the provision of means for cushioning shocks conse-

quent to the sudden and forcible closure of the main valve.

Other objects and advantages will appear 60 as the description proceeds.

An embodiment of the invention is illustrated in the accompanying drawings, wherein:—

Figure 1 is a side elevation illustrating a 65 practical application of the invention wherein in the opening and closing operations of the main and auxiliary valves are initiated and automatically controlled by the closet seat, which seat has a normally elevated position 70 wherein it is substantially perpendicular; Figs. 2 and 3 are vertical longitudinal sectional views, Fig. 2 showing the main and auxiliary valves and the closet seat in their normal positions, and Fig. 3 showing the 75 closet seat depressed, the auxiliary valve closed and the main valve open; Fig. 4 is a horizontal sectional view in the plane of the rock shaft which controls the operation of the valves; Fig. 5 is a fragmentary vertical 80 cross-sectional view in a plane at right angles to Figs. 2 and 3 with the parts related as in Fig. 3; Fig. 6 is a detail horizontal sectional view on the line 6—6 of Fig. 2; Fig. 7 is a detail perspective view of 85 a washer which is employed in the organization of the seat-operated rock shaft; and Fig. 8 is a detail perspective view of a cross 90 head which adjoins the auxiliary valve and forms an element of the operating means. 90

Similar characters of reference designate corresponding parts throughout the several views.

The closet bowl 1 is of any suitable construction and is equipped with a seat 2 95 which normally occupies a substantially vertical position. The water which flushes the bowl is stored in a normally empty tank 3 having a pipe 4 through which water both enters and discharges from said tank. The 100 bowl 1 is equipped with a flush pipe 5 and the pipes 4 and 5 are connected to a normally empty supply pipe 7 which projects for some distance into the ground and at its lower end is joined to a water-main. 105

The pipe 5 is arranged above the pipe 4; and the pipe 7 is provided with two valve seats, one of which 8 is arranged near the lower end thereof and is engaged by a main valve 9 and the other of which 10 is arranged between the points of connection of the pipes 4 and 5 with the pipe 7 and is engaged by an auxiliary valve 11. The valves 9 and 11 are mounted upon a common valve

stem 12, the valve 9 being disposed below its seat 8 and the valve 11 being disposed above its seat 10. By virtue of these features of relation, when the main valve 9 is closed the auxiliary valve 11 is opened, and when the main valve 9 is opened the auxiliary valve 11 is closed. It follows from this that the water which flows into the supply-pipe 7 when the main valve is opened cannot pass directly to the bowl, since the auxiliary valve is closed and, therefore, must pass through the pipe 4 into the tank 3 wherein it accumulates against the pressure of air in the upper portion of said tank. When the relation of the valves is reversed, that is to say, when the main valve is closed and the auxiliary valve is opened, the water stored in the tank 3 in the manner just described flows downwardly through the pipe 4 and enters the supply pipe 7 from which it passes through the pipe 5 to the bowl, flushing the latter. The water which backs up in the supply pipe 7 in connection with the operation of the flushing apparatus escapes through a drain port 13 controlled by the drain valve 14. The drain valve 14 is supported in the closed position of the main valve 9 in spaced relation above the drainage opening 13. However, when the main valve 9 is opened the valve 14 becomes operative to close the drainage opening 13. The valves 9 and 11 are of course correlated by the stem 12 which is common to both of them and their operation is positively effected and controlled by the seat 1 which has as its pivotal axis a rock shaft 15 and in its movements turns said rock shaft and through certain intermediate connections operates the valves. The above features, broadly considered, are well known in the art and the present invention proposes certain specific improvements which are grafted, so to speak, upon the features of construction and organization above explained and which will be clearly brought out as the description proceeds.

The operating means for the valves includes as an essential element the rock shaft 15 above referred to, which rock shaft has its ends journaled in an extension 16 of the pipe 7 arranged above the pipe 5. The said rock shaft carries a V-shaped cam 17 which works in a vertical slot 18 of a cross head 19 and is provided with co-extensive engaging arms 17^a and 17^b. The cross head 19 forms, in effect, a continuation of the valve stem 12, and in the embodiment shown is integral with the auxiliary valve 11. Said cross head has its side bars provided with alining slots 19' through which the shaft 15 projects and which permit said cross head to move vertically and relatively to the shaft 15. The slot 18 alines with a recess 20 at one side of the extension 16 and the

arms of the cam 17 project into the recess 20 in the course of their movement. The cam 17, by the engagement of its arms 17^a and 17^b with the respective upper and lower portions of the cross head 19, is effective to positively raise or lower said cross head and therewith the connected auxiliary and main valves. The cam 17 is of course fast on the rock shaft 15 and its operative movements are due to the turning of said rock shaft, which, in turn, is effected by movements of the seat 2.

The seat 2 is provided, as usual, with a hinge casting having parallel rearwardly-directed arms 21 and 22. The arm 21 carries a trunnion 23 which engages in a bearing 24 provided at one side of the extension 16 and the arm 22 surrounds the shaft 15 which at one end projects beyond the extension 16. The shaft 15 is journaled in a bearing 25 internal to the extension 16 and in a stuffing box 26 at the side of the said extension opposite to said bearing and it is held against endwise displacement by a U-shaped washer 27, (Fig. 7), which is fitted in an annular groove 28 in the shaft 15 and is arranged within the cap of the stuffing box 26. The means for holding the seat 2 in a normally elevated position preferably comprises a counter-weight mounted on an arm 22 and the stuffing box 26. The influence of this counter-balance weight is transmitted to the seat by a bracket 30 having an arm 31 which engages under the arm 29 and an arm 32 which engages under the arm 22. The bracket 30 is fast on the shaft 15 and, therefore, turns said shaft in accordance with the movements of the seat 2. The object in using the bracket 30 as a means of connection between the counter-weight and the shaft 15 is to enable an adjustment of the position of said counter-weight whereby its leverage may be increased or decreased as desired, and such adjustment is effected by a screw 33 carried by the arm 31.

Those portions of the shaft 15 upon which the disk 17 and the bracket 30 are mounted are preferably square or flat sided in cross section and said disk and said bracket have openings for the shaft which conform to its flat sided cross section. The bracket 30 is held in place by a washer 34 which is secured to the shaft 15 by a screw 35 threaded into the outer end face of said shaft. The seat 10 for the auxiliary valve 11 has its opening of greater diameter than the external diameter of the seat 8 for the main valve 9. The said seat 8 is threaded in the lower portion of the pipe 7, or, more strictly, in a reduced extension 36 of said pipe and, being arranged above the valve 9 as previously set forth, may be removed from the pipe 7 with said valve. In removing or replacing the valve seat 8 it is of course necessary to engage or disengage it with respect to the

mating threads in the extension 36, and for this purpose the opening 37 in the valve seat 8 through which the stem 12 passes is somewhat oval or elongated and that portion of the valve stem which normally fits said opening has an elongated cross section, as shown in Fig. 6. In this way if the valve stem be rotated it will turn the seat 8 to engage it or disengage it from the threads in the extension 36. The turning of the valve stem for this purpose is effected by rotating the cross head 19 by means of a suitable tool. When the valve seat 8 has been disengaged from the threads in the extension 36 the operating parts of the device may be removed as a unit from the pipe 7, although in order that such disengagement of said valve seat may be effected, it is of course obvious that the shaft 15 must have been previously withdrawn from its bearings in the extension 16. Those operating parts which are removable as a unit are the cross head 19, the auxiliary valve 11, the main valve 9, the stem 12 which connects and correlates said auxiliary valve and main valve, the main valve seat 8 which is supported on the main valve during its removal, and the drain valve 14.

The drain valve 14 is normally supported in spaced relation above the drain opening 13 by a flange 38 which circumscribes the stem 12 near its lower end. Almost immediately, however, following the initiation of the downward movement of the main valve the valve 14 comes to rest over and closes the drain opening 13. The said valve 14 is preferably in the form of a disk which somewhat loosely surrounds the lower portion of the valve stem 12 and in its lower position, in which it closes the drain opening 13, it rests uniformly upon a shoulder 39 provided at the upper end of the extension 36. In view of the structural character of the drain valve and its relation to the main valve, it is necessary for the water which flows past the main valve to have a by-pass circulation with reference to the drain valve in order that it may not effect the unseating thereof. For this purpose, the stem 12 is preferably made in sections and its lower section, which carries the main valve, is formed with a water duct 40 communicating at its lower end with a water inlet opening 41 and at its upper end with a water outlet opening 42. The opening 41 is arranged slightly above the main valve and almost immediately that the main valve leaves its seat 8, water passes through the opening 41 into the duct 40 and issues from the latter into the pipe 7, the water thus entering the pipe 7 aiding, by its weight or head, in keeping the drain valve closed.

The invention also proposes certain features of construction whereby immediately that the seat is depressed, as shown in Fig. 1,

a short preliminary flush will take place. In order that this result may be positively insured, the upper member of the stem 12 is provided with a water duct 43 which at its lower end communicates with the water inlet openings 44 and at its upper end communicates with water discharge openings 45. The openings 44 are controlled by suitable flap valves 46 which tend to spring outwardly. By virtue of these features of construction a percentage of the water which flows into the pipe 7 will pass through the normally uncovered openings 44 into the duct 43 from whence it discharges through the openings 45 into the flush pipe 5, and this result takes place even though the auxiliary valve 11 be closed. At this point, it may be noted that there will be an interval in the operation of the apparatus when the auxiliary valve 11 and the main valve 9 will be simultaneously open and that the preliminary flush desired would doubtless take place by virtue of this interval of simultaneous opening in the event that the seat 2 were lowered sufficiently slowly to enable the water to reach the flush pipe 5 before the auxiliary valve 11 became seated. However, if this period of simultaneous opening of the auxiliary and main valves were alone relied upon to provide the preliminary flush, such flush would be defeated in those cases where the seat 2 was lowered with sufficient rapidity to insure the closing of the auxiliary valve before the water in the pipe 7 reached the elevation of the pipe 5, but by virtue of the provision of the duct 43 in the valve stem 12 the preliminary flush desired is not affected by or in any way dependent upon the speed with which the seat 2 may be lowered since flush will take place when the auxiliary valve is closed. As above pointed out, the flap valves 46 tend to spring outwardly and to uncover the openings 44 so that when water first enters the pipe 7 it is free to pass through the duct 43 into the flush pipe 5. In the meantime, water is of course rising in the pipe 7 and in the pipe 4, ultimately passing into the tank 6, and when the head of the water thus rising through the pipes 7 and 4 and into the tank 6 has accumulated sufficient force to close the valves 46 against their tendency to spring outward and against the internal pressure of the water in the duct 43, the preliminary flush is arrested. The next flush that takes place is of course the main flush and the interval between the preliminary flush and the main flush corresponds to the interval in which the seat 2 is depressed.

Owing to the short and rapid movement of the main valve 9 to closed position there is a liability, especially where the service pressure is heavy, of the development of an unpleasant water hammer consequent to the closing of said valve and it is, of course,

desirable to eliminate this condition. For this purpose, a special cushioning attachment is joined, integrally or otherwise, to the extension 36, and such attachment comprises a pipe 47 which forms a continuation of the extension 36, and a casing 48 surrounding and inclosing the pipe 47, the casing 48 being joined to said pipe at its upper end and being spaced from said pipe throughout its extent and at its lower end, thus providing an internal air chamber 49 in surrounding relation to the pipe 47 and in which there is an accumulation of air which effectively cushions the shock incident to the closing of the main valve. The casing 48 is formed with a mouth 50 which aligns with the mouth of the pipe 47 and which is suitably threaded for connection to the coupling member which establishes communication between pipe 47 and the water main.

To facilitate the removal of the unitary valve structure, the cross head 19 is provided at its upper side with a square plug 51 which works in a socket 52 of the cap 53 that closes the upper end of the extension 16. The plug 51 has such length that it projects beyond the upper edge of the extension 16, even in the lowest position of the cross head 19. In this way said plug is always accessible for engagement by a wrench or other suitable implement.

In order to remove the unitary valve structure the cap 53 is first removed from the extension 16. Then the cam 19 is turned until its two arms are symmetrically related to the central longitudinal axis of the cross head at which time said cam is wholly out of the recess 20, and the plug 51 is wholly beyond the extension 16 whereby said plug is accessible for engagement by a wrench throughout its length. The shaft 15 is then removed and the unitary valve structure is held in an elevated position and at the same time rotated by the wrench or other implement used. This rotation causes the disengagement of the valve seat 8 from the threads of the extension 36 at which time the whole internal organization may be removed as a unit from the pipe 7. In case the valve structure should be dropped during the operation of effecting its removal, its downward movement will be arrested by the engagement of the auxiliary valve upon its seat 10 but in such position the plug 51 will project to some extent beyond the upper edge of the pipe 17 wherefore the removal of the valve structure may be readily resumed.

The cross head 19 preferably has at its upper side suitably arranged recesses 54 provided for the purpose of enabling an inspection of the cam 17 in connection with the removal of the valve structure in order to determine, in case the valve structure should accidentally be dropped while being

removed, whether the cam 17 has been jarred from position so that it projects into the recess 20. If such should be the case the cam must be disengaged from the recess 20 before the operation of removing the unitary valve structure can be resumed. The displacement of the cam 17 from the cause stated is not liable to occur however since the ends of its arms are somewhat flattened at an angle, in order that they may present flat bearing surfaces to engage the cross head 19 when the cam is turned, as above explained, to bring its arms in symmetrical relation to the central longitudinal axis of the cross head.

The form of cam 17 herein shown is preferred in that it is readily disengageable from the recess 20 in connection with the removal of the suspended valve structure and effects the positive lowering as well as the positive raising of the valve structure. In this way, the auxiliary valve is positively and forcibly held in closed relation and mere gravity is not relied on. Consequently, the accidental upward displacement of the "hammering" of said valve due to an excess pressure of water which might be liable were the seating of the valve impossible, is absolutely prevented.

The operation will be readily apparent from the foregoing description. When the seat 2 is in an elevated position, as shown in Fig. 2, the main valve 9 is closed, the drain valve is open, and the auxiliary valve is open. This relation of parts obtains during and subsequent to the main flush. Any water which may have columned in the pipe 7 incident to the discharge of water from the tank 3 escapes through the drain port 13. In this way the pipes 7 and 4 and the tank 3 are normally empty. When the seat is depressed the auxiliary valve 11 is lowered upon its seat 10 and the main valve 9 is opened, and the drain valve 14 closes the drain port 13. When this relation obtains water flows into the pipe 7 in the manner explained, the water thus entering the pipe 7 flowing in part through the by-pass duct 43 to the flush pipe 5 and producing a preliminary flushing of the bowl and in greater part through the pipes 7 and 4 into the tank 3. When the head of the water in the pipes 7 and 4 becomes sufficient to effect the closure of the valves 46 the preliminary flush is arrested. Subsequently, the seat 2 is restored to its normal elevated position, the main valve is closed and the auxiliary and drain valves are open. Thereupon, the main flush takes place and the excess water escapes through the drainage opening 13, as above explained.

Having fully described my invention, I claim:

1. In a frost-proof closet, the combination with a supply pipe, a tank, a pipe com-

- necting the tank and the supply pipe, a closet bowl, and a flush pipe connecting the supply pipe and the closet bowl, of a main valve arranged at the lower end of the supply pipe, a main valve seat removably fitted in the supply pipe, an auxiliary valve for breaking the communication of the flush pipe and the tank pipe when the main valve is open, a stem connecting and correlating said valves, said main valve, main valve seat, auxiliary valve and connecting stem being removable from and replaceable into said supply pipe as a unit, and operating means for said valves.
2. In a frost-proof closet, the combination with a supply pipe, a tank, a pipe connecting the tank and the supply pipe, a closet bowl and a flush pipe connecting the supply pipe and the closet bowl and leading from the supply pipe at a point above the point of connection therewith of the tank pipe, of a main valve arranged at the lower end of the supply pipe, a main valve seat threaded in the supply pipe, an auxiliary valve for breaking the communication of the flush pipe and the tank pipe when the main valve is open, a stem connecting and correlating said valves, said stem projecting through said main valve seat and being formed to rotate said seat whereby to engage it with or disconnect it from the threads of the supply pipe, said main valve, main valve seat, auxiliary valve and connecting stem being removable from and replaceable into said supply pipe as a unit, and operating means for said valves.
3. In a frost-proof closet, the combination with a supply pipe, a tank, a pipe connecting the tank and the supply pipe, a closet bowl and a flush pipe connecting the supply pipe and the closet bowl and leading from the supply pipe at a point above the point of connection therewith of the tank pipe, of a main valve arranged at the lower end of the supply pipe, a main valve seat threaded in the supply pipe and arranged above the main valve, an auxiliary valve for breaking the communication of the flush pipe and the tank pipe when the main valve is open, a stem connecting and correlating said valves, said stem carrying the main valve at its lower end and having the portion thereof which projects through the main valve seat formed to rotate said seat whereby to engage it with or disconnect it from the threads of the supply pipe, said main valve, main valve seat, auxiliary valve and connecting stem being removable from and replaceable into said supply pipe as a unit, and operating means for said valves.
4. In a frost-proof closet, the combination with a supply pipe, a tank, a pipe connecting the tank and the supply pipe, a closet bowl and a flush pipe connecting the supply pipe and the closet bowl and leading from the supply pipe at a point above the point of connection therewith of the tank pipe, of a main valve arranged at the lower end of the supply pipe, a main valve seat threaded in the supply pipe and arranged above the main valve, an auxiliary valve for breaking the communication of the flush pipe and the tank pipe when the main valve is open, a stem connecting and correlating said valves, said stem carrying the main valve at its lower end and having the portion thereof which projects through the main valve seat formed to rotate said seat whereby to engage it with or disconnect it from the threads of the supply pipe, said main valve, main valve seat, auxiliary valve and connecting stem being removable from and replaceable into said supply pipe as a unit, and operating means for said valves.
5. In a frost-proof closet, in combination, a supply pipe, a tank, a bowl, a flush pipe between the supply pipe and the bowl, a pipe between the supply pipe and the tank, a main valve normally closing the lower end of the supply pipe, an auxiliary valve for establishing or disestablishing the communication of the flush pipe and the tank pipe through the supply pipe and being open when the main valve is closed and closed when the main valve is open, a stem connecting and correlating said valves and having a water duct and upper and lower openings communicating with said duct at the upper and lower sides of said auxiliary valve, and outwardly springing valves operable consequent to pressure external to said duct to close the lower openings.
6. In a frost-proof closet, in combination, a supply pipe, a bowl, a tank, a flush pipe connecting the supply pipe and the bowl, a pipe connecting the supply pipe and the tank, a main valve normally closing the lower end of the supply pipe, an auxiliary valve for establishing or disestablishing the communication of the flush pipe and the tank pipe through the supply pipe and being open when the main valve is closed and closed when the main valve is open, a stem connecting and correlating the valves, a cross head arranged above and fixed to the auxiliary valve and having a vertical longitudinal slot, an upward extension of said supply pipe inclosing said cross head, a rock shaft journaled in the walls of said extension and a cam arranged within said slot and fixed on the rock shaft.

7. In a frost-proof closet, in combination, a supply pipe, a bowl, a tank, a flush pipe connecting the supply pipe and the bowl, a pipe connecting the supply pipe and the tank, a main valve normally closing the lower end of the supply pipe, an auxiliary valve for establishing or disestablishing communication of the flush pipe and the tank pipe through the supply pipe and being open when the main valve is closed and closed when the main valve is open, a stem connecting and correlating the valves, a cross head arranged above and fixed to the auxiliary valve and having a vertical longitudinal slot, an upward extension of said supply pipe inclosing said cross head, a rock shaft journaled in the walls of said extension and a V-shaped cam arranged within said slot and fixed on the rock shaft, the extension having a lateral recess in which the cam works.

8. In a frost-proof closet, in combination, a supply pipe, a bowl, a tank, a flush pipe between the supply pipe and the bowl, a pipe between the supply pipe and the tank, a main valve normally closing the lower end of the supply pipe, an auxiliary valve for establishing and disestablishing the communication of said flush pipe and tank pipe through said supply pipe, a stem connecting and correlating said valves, a cross head arranged above and connected to the auxiliary valve and having a vertical longitudinal slot, an upward extension of the supply pipe surrounding said cross head, a rock shaft journaled in said extension and projecting through slots in the sides of said cross head, the rock shaft having an externally projecting portion, disengageable means for normally preventing endwise displacement of the rock shaft and a cam arranged within said longitudinal slot and mounted upon the shaft to turn therewith but to permit of endwise relative displacement thereof.

9. In a frost-proof closet, in combination, a vertical supply pipe, a bowl, a tank, a flush pipe connecting the supply pipe and the bowl, a pipe connecting the supply pipe and the tank, a main valve normally closing the lower end of the supply pipe, an auxiliary valve for establishing or disestablishing the communication of the flush pipe and the tank pipe through the supply pipe and being open when the main valve is closed and closed when the main valve is open, a stem connecting and correlating the valves, the auxiliary and main valves and their connecting stem forming a unitary element vertically movable in the supply pipe and operating means for said element constructed to act positively thereon in lowering as

well as raising the same and including a transverse rock shaft, an operative connection between said rock shaft and said element, a closet seat positively connected to said rock shaft to turn the same in either direction and a counterbalance means for said closet seat.

10. In a frost-proof closet, in combination, a supply pipe, a bowl, a tank, a flush pipe connecting the supply pipe and the bowl, a pipe connecting the supply pipe and the tank, a main valve normally closing the lower end of the supply pipe, an auxiliary valve for establishing or disestablishing the communication of the flush pipe and the tank pipe through the supply pipe and being open when the main valve is closed and closed when the main valve is open, a stem connecting and correlating the valves, the auxiliary and main valves and their connecting stem forming a unitary element and operating means for said element constructed to act positively therein in lowering as well as in raising the same, said operating means comprising a cross head fixed to said element and having a slot and a cam working in said slot, a transverse rock shaft carrying said cam, a closet seat having said rock shaft as its axis and rigidly connected thereto, and a counterbalance means for said closet seat.

11. In a frost-proof closet, in combination, a supply pipe, a bowl, a tank, a flush pipe connecting the supply pipe and the bowl, a pipe connecting the supply pipe and the tank, a main valve normally closing the lower end of the supply pipe, an auxiliary valve for establishing or disestablishing the communication of the flush pipe and the tank pipe through the supply pipe and being open when the main valve is closed and closed when the main valve is open, a stem connecting and correlating the valves, the auxiliary and main valves and their connecting stem forming a unitary element and operating means for said element constructed to act positively therein in lowering as well as in raising the same, said operating means comprising a cross head fixed to said auxiliary valve and having a slot and an upwardly projecting plug, and a cam working in the slot, the supply pipe having an upward extension which incloses said cross head.

In testimony whereof I have hereunto set my hand in presence of two subscribing witnesses.

EDWARD HOERICH.
